Abrau Haney,

Res. 121

Morrison & Tibbets Assignees of Abram Haney
Letters Patent No. 521, dated May 8th 1879 -

The Schedule referred to in these Letters (Patent and Assigning part of the same).

Should whom it may concern:

(Be it Known that A. Abram Haney of

Troy, in the County of Rensselaer and State of New York, have invented or produced a new design for a stove which I call the "Floral Air Tight Wood Parlor Stove," and I do hereby declare the following is a full and exact description of the same (Reference being had to the annexed drawings, which I desire to make a part of my specification. Figure A. is a perspective view of the stove. Figure B. represents the front & back plates, which are curved, the form of the curve will appear by reference to the line marked No 1 in Fig D. The ends are shown in Fig C. the curve of this plate is also shown in Fig D, by the line marked No 2, and forming with the front and back plates, half round corners. Fig D. is a sectional view of the bottom, the hearth plate is shown as No 3, and the draft damper, is numbered 4. The top is represented as Fig E. in which the quarter of the figure represented is symmetrical with the other three quarters. Fig F. is a perspective view of the top).

What I claim as my invention and desire to secure by Letters Patent is the design of an Air Tight Wood Parlor Stove, as shown and described in the Specification and drawings Figures B. C. D. E.
